PYROTECHNICAL DEVICE

Emanuel B. Hershberg, Stoughton, Mass., and Everett R. Coburn, Bennington, Vt., assignors to the United States of America as represented by the Secretary of War

Application May 22, 1944, Serial No. 536,798

7 Claims. (Cl. 102—90)

1

The invention described herein may be manufactured and used by or for the Government, for governmental purposes, without the payment to us of any royalty thereon.

This invention relates to devices which produce and are activated by a flame, more specifically to demolition igniting devices which are best adapted for their intended purpose when they produce a smooth, silent and timely flame and are waterproof.

Pocket incendiaries and similar demolition devices are exacting in their requirement of a suitable silent igniter. In the ordinary missile and large-size munitions, the usual means for initiating explosion or burning of an incendiary is a percussion primer in which a primary explosive detonant, upon impact by a striker, generally gives off a loud report accompanied by a bright flash. This type of igniter has objectionable characteristics. Although there are certain chemicals and combinations of chemicals which silently produce flame by spontaneous reaction, they have presented difficulties hitherto in forming a simple and compact igniting means with necessary safety provisions for application.

An object of this invention is to provide a demolition device having desirable construction features for economical production, reliable performance and efficient use.

Another object is to provide a pocket incendiary unit which is satisfactorily compact for carrying convenience and secret use.

A further object is to provide an igniter adapted for use in combination with a compact pocket incendiary unit, the igniter being properly timed and silent in its action and being capable of performing its function even after the unit has been immersed in water.

The invention and other objects will be understood from the following description and accompanying drawing.

In the drawing,

Figure 1 illustrates a top view, partly in section, of a pocket incendiary unit embodying principles of the invention.

Figure 2 illustrates an end view of the incendiary unit.

Figure 3 illustrates an enlarged longitudinal view of the initiating igniter device detached from the incendiary unit.

Figure 4 illustrates an enlarged longitudinal view of the initiating igniter device in cross section.

Figure 5 illustrates a fragmentary, partly longitudinal and partly cross-sectional view of a modified form of the invention.

2

Referring to Figure 1, the pocket incendiary unit comprises a case 1 having an attached igniter tube 2, the igniter tube lying contiguously at the sides of the case and being held to the case firmly by a cemented clip 3. The case 1 is constructed in two parts, 4 and 5, the latter being more shallow. The two parts of the case are made from an inflammable material which is not dissolved by hydrocarbon fuel. These parts of the case are 10 economically and satisfactorily made from virgin black cellulose nitrate with an ordinary plasticizer, such as camphor. The larger part of the case, 4, has a small filler hole 6 through which a liquid fuel may be charged. After the case is 15 filled with the fuel, the hole 6 is covered by a small cellulose nitrate disc or cap 7 using collodion or cellulose nitrate with acetone as a cement to seal the hole. It is advantageous to use a granular aluminum soap gelling agent, first placing 20 the soap in the case before cementing the two parts together, then filling the case through hole 6 with a fuel, e. g., Stoddard solvent.

On the side of the case where the ignition-initiating tube is to be attached, that part of the 25 case is given a depressed form 8. The two parts of the case have flanges 9 where they are brought together, and they are cemented together by collodion or cellulose nitrate mixed with acetone.

The igniter tube 2 is held firmly attached to 30 the case by a cellulose nitrate plastic clip 3 which is also cemented to the case by collodion or cellulose nitrate mixed with acetone.

The incendiary fuel charged into the case 1 substantially fills the space therein except for a 35 small void of about 5%.

The assembly and operation of the igniter will be described more particularly with reference to Figure 4. This device, in general, has the shape of a pencil or tube. At one end of the igniter 40 tube 2 is disposed or enclosed friction or strike-anywhere match-head 11. A protective thin disc 12 closure and a needle-point firing pin 13 are in alignment with the match-head 11.

The match-head 11 may be attached to the 45 point of a readily available ordinary office pin 14, the head of the pin being cemented to a plastic disc 15 which forms the base of the tube. Satisfactory operation has been obtained even in using a match-head from commercial strike-anywhere

50 matches sold for household use. However, to insure more efficient functioning, a match-head pellet 16 is firmly embedded in a celluloid cement or preferably a cement of glyptal resin and ethyl acetate as a moisture-resistant binder with an 55 added mixture of potassium chlorate and antimony sulfide, preferably about 12 parts of $KClO_3$

to 1 part Sb_2S_3 . The match-head and cement filling are enclosed in a short tubular capsule of which the body 16 and the end discs 12 and 15 are made of cellulose nitrate. This short tubular compartment is fastened to the larger brass tube at shoulder 17 by collodion cement and crimping at 18.

A readily available commercial phonograph needle serves as a firing pin 13. The firing pin 13 is set into a brass block 18' which normally is held against the pressure of a compressed spring 19 by a looped wire 20 under tension acting as a restraining member. The wire 20 is looped through a small hole 21 in a boss end of block 18. A brass washer 22 is disposed on a shoulder of the block 18 to keep the block in a central position with relation to the side of the tube and the spring.

The other end of the looped wire 20 under tension is wound around the stem of a brass screw 23 which is screwed tightly against a lead washer 24 and into a brass plug 25 at the end of the igniter tube opposite the capsule 16.

A brass partitioning plug 26 is interposed between two sections 2a and 2b of tube 2 to act as a base for one end of spring 19 and to furnish support for a glass ampoule 27 in the end section 2a. The partitioning plug 26 has projection 28 and a groove 29 to serve as fastenings to the brass tube 2b and copper tube 2a and for holding the plug in position. Modeling clay, such as Plasticine or equal, is placed in the groove to serve as a plastic sealing 29'. The looped wire 20 is passed through a hole 30 in the partitioning plug 26 and through the clay. Tufts of absorbent cotton, or similar material, are placed at both ends of the glass ampoule compartment to serve as cushioning supports 31 and 32 for the glass ampoule 27 so as to prevent breakage of the glass by normal or accidental jarring.

The tension wire 20 which acts as a restraining member may be a tinned piano wire having a diameter of about .014 inch. The restraining member may be made of any material and of proper size to withstand the corrosive action for a predetermined length of time.

The glass ampoule or bulb 27 is constructed of a good grade of glass tubing with a wall thickness of about .015 to .025 cm. and the corrosive liquid filling of the ampoule is about 0.45 ml. of a solution consisting in $CuCl_2 \cdot 2H_2O$, distilled water and varied amounts of glycerol, depending on the timing desired. For example, the solution may have a composition of about 15 parts by weight of the cupric chloride dihydrate and about 85 parts by weight of water or contain up to about 74 parts by weight of glycerol with about 10 parts by weight of the cupric salt and about 16 parts by weight of water.

A thin pliable strip of metal 33, e. g. brass, passed through a slot 34 located between the firing pin in a restrained position and the match-head capsule, acts as an additional safety means for preventing the firing pin from piercing the capsule, if by any possibility the firing pin is set in motion prematurely. This strip is removed in arming the incendiary.

The holes 35 and 36 located in the brass tube casing of the firing mechanism serve as vent holes for gaseous products of combustion from the ignited match-head. These holes may be left open, or they may be sealed with a small piece of waterproof tape to prevent access of water and dirt into the casing before arming. The ignitable

substance in the capsule may be formulated to provide at least part or all of the oxygen necessary for combustion; and, accordingly, it is not necessary to have inlet holes in the device for admitting air.

The brass tube section 2b extending from the partitioning plug 26 to the match-head capsule 16 in the igniter tube 2 and which surrounds the firing mechanism preferably has thicker walls, about .03 inch, than the copper tube section 2a extending from the partitioning plug 26 to the screw-head 23 and surrounding the glass ampoule. This latter section 2a may have a wall thickness of about .005 inch so that it yields to a sufficient pressure of about 15 lbs. per square inch between a person's fingers to cause bending of the tube and a crushing of the glass ampoule 27, thereby releasing the corrosive liquid contents which contacts and corrodes the restraining wire member 20 in a predetermined length of time, ranging from a period of about 15 minutes to 25 hours.

For operation, the safety strip 33 is straightened and removed from the slot 34 and the copper tube 2a surrounding the timing and releasing compartment is pressed until the glass ampoule 27 is broken to release the corroding liquid into contact with the tension wire 20. The unit is then planted or thrown where it is intended to cause the incendiary action. After a period predetermined by the strength of the corroding liquid and the corrosion-resistance of the tension wire 20, the wire is broken by corrosion, thus releasing the firing mechanism. Upon the breaking of the tension wire 20, the firing pin 13 is forced by compressed spring 19 to move abruptly toward the capsule and the tip of the match-head contained therein. The sharp needle point of the firing pin 13 pierces the match-head capsule cover 12, then pierces the match-head tip 11, causing the match-head to silently ignite and start the burning of the capsule, which in turn immediately starts the burning of the incendiary case and its fuel contents.

With suitable materials used for constructing the incendiary case and in formulating the fuel contents, the incendiary produces an intense heat. The ignition takes place with very little friction and mainly by a sharp shearing as the sharp point of the needle penetrates the match-head tip. This type of ignition is very quiet and sure.

The igniting material in the capsule 16 preferably should contain ingredients which ignite non-explosively and burn in the absence of air.

For construction of the casing, black virgin stock cellulose nitrate is satisfactory, because this material is adequately waterproof, is resistant to carbonaceous fuel and burns in a silent manner without a bright flame. The plastic in the case preferably should contain sufficient pigment or filler to give the plastic a calcined ash content of about .5% to 2%.

A suitable fuel filling for the case is prepared by mixing with gasoline, naphtha or kerosene, a minor proportion of about 5 to 15% by weight of aluminum soaps which gel the liquid hydrocarbon fuels. Preferred gelling soaps are mixtures of aluminum soaps of fatty acids containing from 8 to about 14 carbon atoms per molecule with aluminum soaps of naphthenic acids. The gel is made advantageously stable if one of the aluminum soaps is a soap of a saturated fatty acid, and another component of the mixture is an aluminum soap of a naphthenic acid or of an un-

saturated fatty acid. For example, an effective gelling mixture consists in equal parts of aluminum soaps of coconut oil acids or aluminum laurate, aluminum oleate and aluminum naphthenate. It has been found best to add the gelling soaps to a high anti-knock gasoline base fuel. The hydrocarbon fuel may contain other additives for thickening or altering burning characteristics, such as rubber, resins, thickening polymers, lamp black, wood flour, nitrated cellulose, or cellulose, pyrophoric metal, and ignition accelerators, such as substances which have a low fire point to insure ready ignition when the incendiary is to be used in a cold climate.

While the different members, such as the delayed timing means, the restraining means, the firing means, and the igniting chemical substance in the capsule have been described as functioning together in a preferred unit, each of these members may be modified or in some instances be omitted without disturbing the functioning of the others. For example, the delayed timing may be omitted by simply unscrewing screw 23 and straightening the end of wire 20 so that it is free to move and directly release the firing mechanism. Also, in place of a delay element before ignition, the delay element, such as a powder train, may follow ignition as in standard types of hand grenade fuses.

In another adaptation of the igniter the capsule 16 is used without either the matchhead pellet 11 or the pin 14 and in lieu thereof the capsule encloses a small glass vial 37 containing a pyrophoric or spontaneously ignitable fluid substance (not shown) such as divinyl acetylene, diethyl zinc, triethyl boron or the like. The glass vial may be cemented inside the plastic capsule with match composition 38 containing a waterproof binder as in the booster mixture described. When the firing pin 13 pierces the plastic cover of the capsule, it crushes the vial, and the fluid ignites the match composition 38 which first ignites the capsule which ignites the inflammable case 1 of the incendiary device. Only about 0.2 to 0.3 cc. of the fluid need be in the vial.

The waterproofed igniter and associated firing mechanism operate with good precision and satisfactory safety in handling. They function particularly well in conjunction with a pocket incendiary but are adapted for other uses, as, for example, in firing smoke munitions, grenades and the like. With the igniting material fully encased until the moment of ignition by the firing pin piercing the plastic cover, the igniting material is kept fully protected and can be fired even when the unit is completely immersed in water.

It is to be understood that although the invention has been described with reference particularly to the pocket incendiary unit illustrated in the drawing, other modifications come within the spirit and scope thereof.

We claim:

1. An incendiary device comprising a cellulose nitrate case containing an incendiary fluid, a tubular case attached to said cellulose nitrate case having a perforated relatively rigid tubular portion and a relatively deformable tubular portion, a silent igniter device comprising a spring-pressed plunger mounted on a helical spring in said rigid portion, a frangible capsule in said deformable portion containing a corrosive liquid, a corrodable tie means adjacent said capsule and extending into each of said portions for holding said plunger in a compressible condition and a flammable capsule in said rigid portion having a match-head

composition therein adapted to be frictionally ignited by said plunger when the frangible portion has been deformed sufficiently to crush said frangible capsule and release said corrosive fluid on said tie means.

2. An incendiary device comprising a cellulose nitrate case containing an incendiary fluid, a tubular case attached to said cellulose nitrate case having a relatively rigid tubular portion and a relatively deformable tubular portion, a silent igniter comprising a spring-pressed plunger mounted on a helical spring in said rigid portion, a frangible capsule containing a corrosive liquid in said deformable portion, a corrodable tie means adjacent said capsule and extending into each of said portions for holding said plunger in a compressible condition and a second capsule having a pyrophoric composition therein adapted to be ignited by said plunger rupturing said second capsule subsequent to the deformable portion being deformed sufficiently to crush said frangible capsule, and discharge said corrosive fluid on said tie means.

3. An incendiary device comprising a cellulose nitrate case containing an incendiary fluid, a tubular case having a relatively rigid tubular portion and a relatively deformable tubular portion attached to said cellulose nitrate case, a silent igniter comprising a spring-pressed plunger mounted on a helical spring in said rigid portion, a frangible capsule containing a corrosive liquid in said deformable portion, a corrodable tie means adjacent said frangible capsule and extending into each of said portions for holding said plunger in a compressible condition and a capsule having a fluid pyrophoric composition therein adapted to be ignited by said plunger subsequent to the deformable tubular portion being deformed sufficiently to crush said frangible capsule and discharge said corrosive fluid on said tie means.

4. An incendiary device comprising a cellulose nitrate case containing an incendiary fluid, a tubular case having a relatively rigid tubular compartment and a relatively deformable tubular compartment attached by flammable means to said cellulose nitrate case, a silent igniter comprising a spring-pressed plunger mounted on a helical spring in said rigid compartment, a frangible capsule containing a corrosive liquid in said deformable portion, a corrodable tie means adjacent said capsule and extending into each of said portions for holding said plunger in a compressible condition and a flammable capsule having a match-head composition therein adapted to be frictionally ignited by said plunger subsequent to the frangible compartment being deformed sufficiently to crush said frangible capsule and discharge said corrosive fluid on said tie means.

5. An incendiary device comprising a cellulose nitrate case containing an incendiary fluid, a tubular case having a relatively rigid tubular compartment and a relatively deformable tubular compartment attached by flammable means to said cellulose nitrate case, a silent igniter comprising a spring-pressed plunger mounted on a helical spring in said rigid compartment, a frangible capsule containing a corrosive liquid in said deformable compartment, a corrodable tie means adjacent said capsule and extending into each of said compartments and in said spring for holding said plunger in a compressible condition and a flammable capsule having a fluid pyrophoric composition and a match-head com-

position therein adapted to be frictionally ignited by said plunger subsequent to the deformable compartment being deformed sufficiently to crush said frangible capsule and discharge said corrosive fluid around said tie means. 5

6. An incendiary device comprising a cellulose nitrate case containing an incendiary fluid, a tubular case having a relatively rigid tubular compartment and a relatively deformable tubular compartment attached by flammable means 10 to said cellulose nitrate case, a silent igniter comprising a spring-pressed plunger mounted on a helical spring in said rigid compartment, a frangible capsule containing a corrosive liquid in said deformable compartment, a corrodable tie means adjacent said capsule and extending into each of said compartments for holding said plunger in a compressible condition and a flammable capsule having a fluid pyrophoric composition therein adapted to become ignited subsequent to the deformable compartment being deformed sufficiently to crush said frangible capsule and discharge said corrosive fluid on said tie means. 15

7. A silent igniter comprising a cellulose nitrate case having a relatively rigid tubular compartment and a relatively deformable portion, a spring-pressed plunger mounted on a helical spring in said rigid compartment, a frangible capsule containing a corrosive liquid in said deformable portion, a corrodable tie means adjacent said capsule and extending into each of 20 25 30

8 said portions for holding said plunger in a compressible condition and a flammable capsule having a match-head composition therein adapted to be frictionally ignited by said plunger subsequent to the deformable portion being deformed sufficiently to crush said frangible capsule and discharge said corrosive fluid on said tie means.
